UNITED STATES PATENT OFFICE.

FREDERICK J. HARDMAN, OF DAYTON, OHIO, ASSIGNOR, BY MESNE ASSIGNMENTS, TO DELCO-REMY CORPORATION, OF DAYTON, OHIO, A CORPORATION OF DELAWARE.

ENGINE-STARTING APPARATUS.

Application filed July 15, 1924. Serial No. 726,212.

This invention relates to an electrical engine starting apparatus for internal combustion engines and more particularly to the type which includes an electrical motor and 5 connections between the motor and the engine including a pinion normally demeshed from a gear connected with the engine, said connections including means whereby, when the engine starts, the pinion will be automatically demeshed from the engine gear. The pinion is moved into mesh with the gear by pedal operation. During the movement of the pinion into position for starting the engine, the pedal is automatically disengaged from the pinion so that the pinion will be automatically demeshed when the engine becomes self operative regardless of failure to release the pedal.

It is one of the objects of the present invention to minimize the shock of engagement of the gear teeth when the motor begins to operate with engine cranking torque. One manner of accomplishing this is to cause the motor to operate at a relatively slow speed 20 to facilitate engagement of the motor pinion with the engine gear, and to provide for withholding the full cranking current from the motor until the pinion is very nearly in full engagement with the engine gear. 25 Further objects and advantages of the present invention will be apparent from the following description, reference being had to the accompanying drawings, wherein a preferred embodiment of one form of the present invention is clearly shown.

In the drawings:

Fig. 1 is a fragmentary side view partly in section of the starting apparatus embodying the present invention;

Fig. 2 is a view similar to Fig. 1 with the apparatus in position for cranking the engine;

Fig. 3 is a wiring diagram showing the circuits for producing slow rotation of the motor prior to engine cranking and also the engine cranking circuit.

The engine is not shown in the drawing but is represented by a flywheel gear 20 which is adapted to be driven and to drive 50 a pinion 21 which is threadedly engaged by spiral splines 22 formed on the motor shaft 23 of the motor 24. The motor 24 includes a field frame 25 attached to a left end frame not shown and to the right end frame or 55 gear housing 26. The two end frames pro-

vide bearings for the shaft 23, one of these bearings being shown at 27. To the shaft 23 is pinned or otherwise secured a stop collar 28 for receiving a thrust of pinion 21 when driving the gear 20. Between bearing 60 27 and the thrust collar 28 there is located a thrust washer 29 for receiving the thrust of the pinion 21 transmitted through the collar 28.

The hub 30 of pinion 21 is provided with 65 flanges 31 and 32 including a groove 33 which receives the arms of a pinion shifting arm or lever 34 pivoted on rod 35, the arms of the lever being connected by a yoke 36. A spring 37 surrounding the rod 35 bears at 70 end 38 upon the housing 26, and at the end 39 upon yoke 36. The spring 37 therefore urges the lever 34 in clockwise direction so that the flange 31 is normally maintained against a stop 40 integral with the shaft 23 75 or provided by a tubular sleeve surrounding the shaft.

The mechanism for operating the lever 34 includes a pedal 41 connected by a pedal rod 42 with a lever 43 which is pivotally connected with the rod 35. Motion from the lever 43 is transmitted to the lever 34 by a pin 44 connected with lever 43 which pivotally supports a link member or pawl 45 adapted to engage a notch 46 provided by 80 lever 34. The spring 47 surrounds the pin 44 and bears at one end 48 against a stud 49 attached to lever 43, and at the end 50, against an ear 51 integral with and at right angles to the pawl 45. The spring 47 therefore 85 yieldingly urges the pawl 45 in a counterclockwise direction so that the pawl tends to return to the position shown in Fig. 1.

The mechanism for disengaging pawl 45 from the lever 34 includes a roller 60 attached to a bracket 61 connected to a plunger rod 62 which is slidable through posts 63 and 64. The rod 62 is attached to a collar 65. The spring 66 included between the post 64 and the collar 65 tends to maintain 100 the collar 65 against the post 63.

The switch mechanism for causing the motor to operate relatively slowly includes a non-conducting block 70 attached to rod 62 and adapted to engage and move downwardly a resilient contact arm 71 carrying a contact 72 for engaging contact 73 as indicated in Fig. 1. Contacts 72 and 73 are connected with a battery 74 and with an auxiliary high resistance field winding 75 of 110

the motor 24 which is provided with a low resistance series field 76 and armature 77.

The mechanism for causing the motor to operate the motor to crank the engine includes lever 43 provided with an adjustable screw 80 for engaging the plunger 81 of a motor switch 82 including, as indicated in Fig. 3, a movable contact 83 and stationary contacts 84 and 85. These contacts are located within the switch case, and one of the contacts 85 is connected with a terminal 86 for connecting the switch with the battery 74. The other contact 84 is connected with field winding 76 of the motor. The switch 82 is secured by screws 87 with the motor frame 25.

The apparatus is restored to normal position by a spring 90 located between the pedal 41 and a cup shaped member 91 provided with a hole through which the rod 62 passes, and supported by the floor board 92 of the automobile.

The operation of the invention is as follows:

Downward pressure of the pedal 41 causes the lever 43 to move downwardly carrying the pawl 45 which engages the lever 34 and actuates the pinion toward the right of the drawings. During this movement, the ear 51 of pawl 45 is engaged by the roller 60 and the spring 66 is pressed beyond its natural state of compression. The spring 66 tends to move the pawl 45 clockwise and out of engagement with the lever 34, but this separation will not occur immediately on account of friction between the pawl 45 and the lever 34. The notch 46 and the end of pawl 45 are shaped so that, while pedal 41 is transmitting motion to the pinion 21, friction between the parts 45 and 34 will be greater than the force exerted by the spring 66 tending to move the pawl 45 out of the notch 46.

Movement of the rod 62 to the left causes the contacts 72 and 73 to be closed to connect the motor 24 with the battery 74 through the high resistance field 75. As the pinion 21 approaches the pinion 20 it is rotated slowly to facilitate meshment with gear 20. Continued pressure upon the pedal 41 causes the pinion 21 to continue to move toward the collar 28; and, when the pinion 21 is closely adjacent the collar 28, the motor switch 82 will be closed. This operation causes the contact 83 to engage contacts 84 and 85 and to cause the motor to crank the engine.

Before the switch 82 is closed, the bracket 61 is stopped by switch post 63. Since movement of roller 60 to the left is prevented, further downward movement of pedal 41 causes the pawl 45 to be disengaged from lever 34. The lever 34 is entirely released from the pedal by the time the main switch 82 is closed.

Fig. 2 shows the apparatus in position

while cranking the engine. After the engine has become self-operative the motor will be disconnected from the engine by virtue of the superior rotation of the engine gear 20 relative to the pinion 21 which rotation causes the pinion 21 to be automatically threaded out of engagement with the gear 20. This demeshment will occur without hindrance from the depressed pedal 41 because the levers 34 and 43 are then disconnected.

To restore the starter into normal position and disconnect the motor from the battery the pedal 41 is released, whereupon the spring 90 will move lever 43 clockwise to restore the pawl 45 to engagement with the notch 46. The spring 66 will restore the rod 62 to normal position thereby permitting the blade 71 to separate the contact 72 from the contact 73. Release of the plunger 81 will permit the spring 88 to return the plunger 81 to normal position and separate the contact 83 from contacts 84 and 85. Therefore the motor will be disconnected from the battery.

One of the main advantages of the present invention is that the gears can be engaged with substantially no shock tending to destroy the gear teeth. While there is some clearance between the pinion 21 and stop 28 when the main motor switch 82 is closed this clearance is so small that the momentum acquired by the pinion 21 during its endwise movement is very small. Consequently the energy to be absorbed by the mechanism when this endwise movement suddenly changes to rotation, is insufficient to cause injury to the gear teeth.

What I claim is as follows:

1. Engine starting apparatus comprising, in combination, a gear connected with an engine to be started; an electric motor; connections between the motor and gear including a pinion and means whereby the pinion will be automatically demeshed from the engine gear when the engine starts; a switch for controlling a circuit for effecting relatively slow operation of the motor; a switch for controlling a circuit for effecting relatively high torque operation of the motor; means for closing the first switch to facilitate gear tooth registration, for moving the pinion into mesh with the engine gear, and then for closing the second switch, said means including a pedal and pinion shifting member; and means including the actuator of the first switch for effecting the disconnection of the pedal and pinion shifting member after the pinion has been meshed with the engine gear.

2. Engine starting apparatus comprising, in combination, a gear connected with an engine to be started; an electric motor; connections between the motor and gear including a pinion and means whereby the pinion

- will be automatically demeshed from the engine gear when the engine starts; a pedal operated lever; a pinion shifting lever; a pawl pivoted on one lever and normally engaged from the pinion lever; and a second switch closed by operation of the pedal lever for effecting the engine cranking operation of the motor.
5. Engine starting apparatus comprising, in combination, an electric motor, a spirally splined shaft operated by the motor, a pinion driven by said splines and movable endwise into mesh with a gear of an engine to be started, an arm for shifting the pinion, a pedal normally actuating the arm; a switch for controlling a circuit for effecting relatively low torque operation of the motor, means including the actuator of said switch for effecting the disconnection of the pedal and pinion shifting arm after the pinion has been meshed with the engine gear, and a second switch operated by the pedal for effecting the engine cranking operation of the motor. 45
6. Engine starting apparatus comprising, in combination, a gear connected with an engine to be started; an electric motor; connections between the motor and gear including a pinion and means whereby the pinion will be automatically demeshed from the engine gear when the engine starts; a pedal operated lever and a pinion shifting lever concentrically pivoted; a spring pressed pawl pivoted on the pedal lever and engaging a notch provided by the other lever; a switch for closing a circuit for effecting relatively slow operation of the motor, said switch having a plunger normally biased in switch-open position and arranged in the path of movement of the pawl but moved by the pawl to close the switch while the pawl remains connected to the pinion lever to move the pinion into engagement with the engine gear; a stop arresting further movement of the plunger after said pinion engagement whereby further movement of the lever will cause the pawl to be disconnected from the pinion lever; and a second switch closed by operation of the pedal lever for effecting the engine cranking operation of the motor. 50
7. Engine starting apparatus comprising, in combination, an electric motor, a spirally splined shaft operated by the motor, a pinion driven by said splines and movable endwise into mesh with a gear of an engine to be started, an arm for shifting the pinion, a pedal normally actuating the arm; a switch for controlling a circuit for effecting relatively low torque operation of the motor, means including the actuator of said switch for effecting the disconnection of the pedal and pinion shifting arm after the pinion has been meshed with the engine gear, and a second switch operated by the pedal for effecting the engine cranking operation of the motor. 55
8. Engine starting apparatus comprising, in combination, an electric motor, a spirally splined shaft operated by the motor, a pinion driven by said splines and movable endwise into mesh with a gear of an engine to be started, an arm for shifting the pinion, a pedal normally actuating the arm; a switch for controlling a circuit for effecting relatively low torque operation of the motor, a link for transmitting motion from the pedal to the arm, an actuator for said switch engaged by said link during movement of said pedal whereby to operate the switch and to disable the link, and a second switch operated by the pedal for effecting the engine cranking operation of the motor. 60
9. Engine starting apparatus comprising, in combination, an electric motor, a spirally splined shaft operated by the motor, a pinion driven by said splines and movable endwise into mesh with a gear of an engine to be started, an arm for shifting the pinion, a pedal normally actuating the arm; a switch for controlling a circuit for effecting relatively low torque operation of the motor, a link for transmitting motion from the pedal to the arm, an actuator for said switch engaged by said link during movement of said pedal whereby to operate the switch and to disable the link, and a second switch operated by the pedal for effecting the engine cranking operation of the motor. 65
10. Engine starting apparatus comprising, in combination, an electric motor, a spirally splined shaft operated by the motor, a pinion driven by said splines and movable endwise into mesh with a gear of an engine to be started, an arm for shifting the pinion, a pedal normally actuating the arm; a switch for controlling a circuit for effecting relatively low torque operation of the motor, a link for transmitting motion from the pedal to the arm, an actuator for said switch engaged by said link during movement of said pedal whereby to operate the switch and to disable the link, and a second switch operated by the pedal for effecting the engine cranking operation of the motor. 70
11. Engine starting apparatus comprising, in combination, an electric motor, a spirally splined shaft operated by the motor, a pinion driven by said splines and movable endwise into mesh with a gear of an engine to be started, an arm for shifting the pinion, a pedal normally actuating the arm; a switch for controlling a circuit for effecting relatively low torque operation of the motor, a link for transmitting motion from the pedal to the arm, an actuator for said switch engaged by said link during movement of said pedal whereby to operate the switch and to disable the link, and a second switch operated by the pedal for effecting the engine cranking operation of the motor. 75
12. In testimony whereof I hereto affix my signature.

FREDERICK J. HARDMAN.
